UNITED STATES PATENT OFFICE.

ADDISON G. WATERHOUSE AND JOHN S. FORBES, OF PHILADELPHIA, PENNSYLVANIA, ASSIGNORS TO WATERHOUSE-FORBES CO., OF SAME PLACE.

APPARATUS FOR HEATING AND STERILIZING FLUIDS.

SPECIFICATION forming part of Letters Patent No. 638,192, dated November 28, 1899.

Application filed November 14, 1898. Serial No. 696,482. (No model.)

To all whom it may concern:

Be it known that we, ADDISON G. WATERHOUSE and JOHN S. FORBES, citizens of the United States, residing at the city of Philadelphia, in the State of Pennsylvania, have invented a new and useful Apparatus for Heating and Sterilizing Fluids, of which the following is a specification.

Our invention relates to the art of heating water, milk, and other fluids for the purpose of destroying disease-germs; also, for producing chemical effects and other useful purposes in the arts.

We are aware that attempts have been made to form automatic sterilizers whereby milk and other fluids could be heated to a predetermined temperature; but in these cases the flow of the fluid was regulated by valves or other mechanical contrivances which possessed the inherent defects peculiar to mechanical contrivance or the positive objection to valves on the score of leakage, corrosion, and unreliability, and also automatic heaters and sterilizers have been made and used wherein the fluid to be treated is drawn from a source of supply below the level required for causing it to flow through the apparatus, and wherein means are employed for causing the fluid to pass through the apparatus as it is raised above its normal level while in a state of ebullition caused by raising the fluid to the boiling-point by the application of heat. There are two objections to the last-above-mentioned methods. The first objection rests upon its limited range of utility for the treatment required for different fluids, and various purposes call for a wide range of temperature above and below the boiling-point. Therefore the state of ebullition which is incidental to the boiling-point is not available as a means of regulation in cases where the boiling-point does not correspond with the temperature required for treating different fluids or for effecting various results—as, for instance, in sterilizing milk, which must be treated at a temperature below its boiling-point in order to avoid cooking the same and impairing its quality. In such fluid, therefore, it is necessary to avoid boiling the same or causing the state of ebullition and still employ means which are incidental to the treat-

ment under which the fluid passes for automatically regulating the flow of such fluid to accord with any predetermined temperature at which it is to be treated.

55

To avoid the objection to the above-named methods, we have made this present invention, which embraces means for employing indirectly the expansive effect of any degree of heat without causing ebullition, which may be applied to the fluid under treatment for automatically causing and controlling the flow of such fluid through the apparatus. The same results can be accomplished by employing directly the expansive effect of heat on the fluid under treatment by means which we reserve for a subsequent application.

60

Our present invention further consists of means for conserving the heat applied by transferring the heat imparted to the fluid on its way from where heat is applied to the cold fluid to be treated while on its way to where heat is applied, and also of certain details and parts belonging to and adapted for the carrying out of our invention.

70

Therefore the leading object of our invention is to form an apparatus which shall possess the inherent elements necessary for automatically performing the following functions: first, heating all the fluid being treated to any predetermined temperature; second, preventing any of the fluid being treated from passing through the apparatus by leaks or otherwise until it has been raised to the desired temperature, and, third, preventing the fluid being treated from being overheated.

75

In order to fully set forth our invention, reference will be had to the accompanying drawings, made a part hereof, in which—

Figure 1 shows diagrammatically an apparatus embodying the different parts of our invention. Fig. 2 is a sectional plan of a heat-exchange. Fig. 3 is a sectional elevation of part of Fig. 2. Fig. 4 is a sectional view of a modified form of heat-exchange.

90

Fig. 1 shows diagrammatically a supply-pipe a and a closed receiving-tank a' , having a valve a^2 , actuated by a float a^3 . C is a pipe which extends downward from a' to a heat-exchange E , consisting of two separate compartments d and i , which are formed within the outer shell of E by means of the partition

95

100

R. The pipe C, which leads from tank a' , enters at the lower extremity of compartment d . At the upper extremity of d is an aperture d' , leading into a closed heater H. Within H 5 is a closed air or vapor chamber L, which is connected by a tube L' to the tank a' , so that there is an air communication leading from the chamber L to the part of the tank a' above the water-level S. The tube L' may be 10 provided with an air-pump L², as shown, for regulating the initial pressure in L. Leading from the top of the heater H is a pipe or passage h, which extends upward above the water level S to a level represented by T, where the 15 pipe takes a downward turn and forms a weir or overflow-aperture f and then extends down, as shown by pipe h', and enters the upper extremity of the compartment i of the heat-exchange E. From the lower end of compartment i the pipe j extends, which terminates at the discharge K. H' represents a gas-burner or means of applying heat to the heater H.

In operation, the fluid to be treated enters 25 at the supply-pipe a into the closed tank a' and passes down through the pipe c until it fills the compartment d and the heater H and rises in the pipe h to the water-level S. When the fluid reaches the level S in pipe h, it also 30 rises to the same level in the closed tank a' . This raises the float a^3 and closes the valve a^2 , so that the fluid is restrained from rising above the level S, but is allowed to pass through the valve a^2 when the fluid is below 35 that level. So when the entering fluid is restrained or limited to the level S it is obvious that it cannot flow over the weir f in pipe h and pass through the apparatus, because the weir f is above the level S or at the higher 40 level T. Therefore the fluid will stop flowing after it rises to the level S in tank a' and pipe h and come to a standstill. If heat is applied to the heater H until the temperature of the fluid is raised to a higher temperature than 45 it had when entering a, the heated fluid in H, which surrounds the closed air vessel L, will expand the air in L and cause it to flow through the tube L' and exert a pressure upon the fluid in tank a' , and this air-pressure in 50 pressing down upon the surface of the fluid in a' will cause the fluid to rise in pipe h to a level above that of S, and the level to which it will rise depends upon the amount the air in L is expanded, which in turn depends upon 55 the degree of temperature to which the fluid in H, and consequently the air in L, is raised. The weir f can be adjusted to a proper height above the level S to correspond to the temperature at which it is desired to treat the 60 fluid. It is obvious under these conditions that as a certain degree of heat will raise the fluid in pipe h to the level necessary to overflow the weir f any less heat than that required will fail to raise it to the overflow- 65 level, so that it will not pass through the apparatus. While, on the other hand, any excess of heat will raise it above the weir f

and cause it to overflow more rapidly, thereby causing it to pass through the heater at a speed which would be beyond the capacity of the heat applied to overheat the fluid. Therefore the apparatus is capable of preventing any fluid from passing through it until it is raised to the required temperature and causing it to flow at a rate which will be 70 beyond the capacity of the applied heat to overheat the same. After the heated fluid passes over the weir f it flows down through pipe h' and fills the compartment i of the heat-exchange E, and while this fluid is passing 75 down through the compartment i its heat is being conducted through the partition R to the cold fluid passing up through the compartment d, so that by the time the heated fluid reaches the lower extremity of compartment i and is ready to pass off through pipe j and discharge K it is cooled down to nearly its original temperature, while the cold fluid which enters the lower extremity of compartment d absorbs this heat, and by the time it 80 reaches the heater H it is raised to nearly the desired temperature. Therefore but a small amount of heat is required to operate the apparatus, as the same heat is conserved and used over and over again. 85

In the construction of this apparatus several important details are involved, one leading feature being the heat-exchange (represented by E in the drawings.) The main object to attain in constructing these exchanges 90 is to produce the greatest practical surface in the partition R, so as to facilitate the transfer of heat from the fluid in one compartment to that in the other; also, to form this partition so that if any leak occurs owing to imperfect joints these leaks will occur from the compartments outward through the joints of the external shell and not from one compartment to the other; also, to have the external shell compact, so as to possess the least possible surface through which heat can be lost into the surrounding air, and in case of small apparatus or where they are made in short or compact form to have the compartments formed so that the movement of the fluid 95 through them will meet with the least possible resistance in order that agitation may be avoided and the fluid be allowed to stratify, so that each part will take a level according to its temperature, ranging so that the hottest 100 will be on top and the coldest at the bottom, or so that the hot fluid in one compartment will sink as it gradually gives up its heat until it passes out through the bottom cold, while the cold fluid in the other compartment 105 will rise as it gradually absorbs heat until it passes out at the top hot. With these objects in view we have constructed a heat-exchange, as represented by Fig. 2, which shows a sectional end or top view. Its outer shell is composed of two light shells E' and E², placed together as shown, with the intervening partition R so that it will extend from the joint E³ across the interior space formed by these 110

shells until it reaches the joint E⁴. The form of this partition R is that of a many-counter-folded sheet, so that it crosses from E³ to E⁴ in a back-and-forth direction and offers a 5 large surface compared to that of E' and E². These three parts are all held together by flanges or riveted joints E³ and E⁴ and then dipped in melted metal, such as zinc or tin, so that the joints are closed and the surface 10 of the metal is coated. This partition R divides the inner space into two compartments d and i. If there is any leak from the joints E³ or E⁴ from either compartment, it will be outward through the outer shell or through 15 these joints and not from one compartment to the other. The fluids enter at the extremes of the compartments d and i and have a straight passage in a direction parallel to the partition R. Fig. 3 is a sectional elevation 20 showing the folded partition R. One of the ends of this exchange is closed by means of cement or metal cast or molded while in a liquid state in the form shown by P, which stops off all the openings at the end of partition R and also completely closes each end of 25 the two compartments formed on each side of this partition.

Fig. 4 shows a heat-exchange, in which E' represents a case inclosing two sides and the 30 top and bottom of the partition R. The ends (not shown) are closed by metal cast in, as described in Fig. 3. In this form the two compartments are made accessible by removing the front and back plates E² and E³.

35 What we claim as our invention is—

1. In a fluid-heater as described, the combination of a closed supply-tank provided with means for maintaining a constant level to the fluid supplied thereto, a closed expansion-chamber having a passage leading from the same to the surface of the fluid in the supply-tank, and means for conducting heat from the fluid being treated, to the air or 40

liquid in the expansion-chamber, whereby the pressure caused by the expansive effect of 45 heat within the expansion-chamber, will force the heated fluid within the apparatus, to a level above its normal point, and cause the same to pass through the apparatus; substantially as described. 50

2. In a fluid-heater as described, the combination of a closed supply-tank with means for maintaining the fluid-level therein constant, a heat-exchange through which the fluid passes on its way to and from the point 55 where heat is applied, a closed expansion-chamber containing air or liquid with means for conducting heat from the heated fluid to the air or liquid within the expansion-chamber, and means for employing the expansive 60 force of the heat conducted to the air or fluid within the expansion-chamber for causing the heated fluid to rise and flow over a weir above its normal level substantially as described. 65

3. A heat-exchange composed of two elongated parallel compartments divided by a folded back-and-forth partition and inclosed around its side by shells provided with inlet and outlet apertures at the extremes of each 70 compartment, and being closed at the ends by cast material adapted for forming an impervious separation between the two compartments; substantially as and for the purposes set forth. 75

4. A heat-exchange composed of two half-shells E' and E², the folded partition R extending out through the joints E³ and E⁴ and the cast sealing material P at the end; substantially as and for the purposes set forth. 80
